[57] CLAIM

The ornamental design for an insect catcher, as shown and described.

DESCRIPTION

FIG. 1 is a perspective view of an insect catcher, showing my new design;

FIG. 2 is a top plan view thereof;

FIG. 3 is a bottom plan view thereof;

FIG. 4 is a rear elevational view thereof;

FIG. 5 is a side elevational view of the opposite side of FIG. 1;

FIG. 6 is a front elevational view thereof;

FIG. 7 is a side elevational view thereof with upper part closed;

FIG. 8 is a side elevational view thereof with upper part open;

FIG. 9 is a side elevational view with the supporting arms attached respectively to the rear and bottom of the upper part thereof; and,

FIG. 10 is a side elevational view of FIG. 9 with the upper part in the open position.
